ATTORNEY

UNITED STATES PATENT OFFICE

EDWARD WITTCOFF, OF ST. LOUIS, MISSOURI, ASSIGNOR TO SUPERIOR HAT COMPANY,
OF ST. LOUIS, MISSOURI, A CORPORATION OF MISSOURI

HAT

Application filed June 24, 1929. Serial No. 373,270.

This invention relates generally to head-wear. More particularly, my invention relates to a certain new and useful improvement in hats especially of so-called harvest type and has for its chief object the provision of a harvest or other hat with a simple, inexpensive, and efficient crown-ventilator.

And with the above and other objects in view, my invention resides in the novel features of form, construction, arrangement, and combination of parts hereinafter described and pointed out in the claims.

In the accompanying drawing,

Figure 1 is a perspective view of a hat embodying a ventilator of my invention;

Figure 2 is a fragmental front elevational view of the hat;

Figure 3 is a fragmental elevational view of the hat looking from the inside; and

Figure 4 is an enlarged fragmental vertical sectional view taken approximately on the line 4—4, Figure 2.

Referring now more in detail and by reference characters to the drawing, which illustrates a preferred embodiment of my invention, A designates the hat proper, which may be of any standard or approved type and which, as is usual, comprises a crown 1 and a brim 2 constructed of straw, fabric, or other suitable material.

Formed preferably in the front of the crown 1, is a circular opening, as at 3, of somewhat reduced diametrical dimension relatively to a disk 4 of wire or other suitable reticulated or open mesh material, whose peripheral margin is suitably curled or folded, as at 5, about a ring 6, as best seen in Figure 3, ring 6 being adapted for placement against the inner surface of the crown 1 and about the rim of the opening or aperture 3 with the mesh-disk 4 stretched thereover, as shown.

Adapted for placement against the outer surface of the crown 1 and also about the rim 45 of the opening or aperture 3, is an approxi-

mately flat ring 7 provided peripherally with an annular series of rearwardly presented prongs 8 adapted for piercing projection through the crown 1 and to be then clinched over and upon the ring 6, whereby both the rings 6 and 7 are securely engaged with the crown 1 and the mesh-disk 4 retained in crown-ventilating position over the opening 3. Preferably the outer ring 7 is re-enforced and also attractively embellished with a preferably integral spider 9.

The ventilator as a whole is inexpensive, is readily and conveniently attached to and upon the hat, and is efficient in the performance of its intended functions.

It is to be understood that changes or modifications in the form, construction, arrangement, and combination of the several parts of my hat-ventilator may be made and substituted for those herein shown and described without departing from the nature and principle of my invention.

Having thus described my invention, what I claim and desire to secure by Letters Patent is:

1. A hat ventilator including, in combination, a first ring, a section of mesh-material disposed over the area of and marginally folded about the ring, a second ring, and an annular series of prongs extending from the outer margin of the second ring adapted for projection through the crown of a hat and for clinching engagement about the first ring for securing said rings together and the ventilator to a hat.

2. In combination, a hat having crown provided with a circular opening in the wall thereof and a ventilator for said opening, the ventilator including a first ring, a section of mesh-material disposed over the area of and marginally folded about the ring, the ring being adapted to fit against the inner face of the crown and about the rim of said opening, a second ring, and an annular series of prongs extending from the outer

margin of the second ring adapted for piercing projection through the crown and for clinching engagement with the first ring for securing said mesh-section over said opening, the second ring at its inner periphery extending over and concealing the rim of said opening.

In testimony whereof, I have signed my name to this specification.

10 EDWARD WITTCOFF.
